J. L. BARRY

DEVICE FOR FORMING YARN PACKAGES

Filed July 12, 1927

John L. Barry
by *Greenwood* Atty

UNITED STATES PATENT OFFICE.

JOHN L. BARRY, OF HINGHAM, MASSACHUSETTS, ASSIGNOR TO CYNTHIA MILLS, OF BOSTON, MASSACHUSETTS, A CORPORATION OF MASSACHUSETTS.

DEVICE FOR FORMING YARN PACKAGES.

Application filed July 12, 1927. Serial No. 205,168.

This invention relates to the packaging of yarn, thread and the like which is commonly retailed in units of skeins of comparatively small quantity.

5 In my co-pending application Serial No. 205,167 filed July 12, 1927, I have disclosed a package holding a number of small skeins of yarn or the like, one element of the package comprising a card having a plurality of 10 spaced upstanding tabs between which the skeins are disposed and by which they are gripped and held against lengthwise displacement on the card as the yarn is withdrawn from the end of the skein. In said application, I have disclosed a device for holding 15 the tabs in upright position while the skeins of yarn are being placed therein. The present application is a continuation in part of said application and is directed to said 20 device.

An object of this invention is the provision of a device adapted to be used to facilitate the forming of yarn packages and specifically to hold the tabs of the above described card in 25 elevated position to receive skeins of yarn therebetween.

A further object is generally to improve package forming devices and methods.

Fig. 1 is a plan view of the package with 30 which this invention is concerned.

Fig. 2 is a side view of the package of Fig. 1.

Fig. 3 is a section along line 3—3 of Fig. 1 and illustrating particularly the skein holding 35 tabs.

Fig. 4 is a perspective detail showing particularly the tab construction.

Fig. 5 is a plan view of the skein holding card of Figs. 1 through 4.

40 Fig. 6 is a perspective view of the tab raising device embodying the present invention.

Fig. 7 is a sectional view taken along line 7—7 of Fig. 6 but in addition illustrating one of the cards of Fig. 5 in position therein.

45 Fig. 8 is a view taken along the same location as Fig. 7, but with the device in operated position and holding the tabs in elevated position to receive the skeins.

Fig. 9 is a view along line 9—9 of Fig. 8.

50 Fig. 10 is a view similar to Fig. 7 but with the card filled with skeins and with the filled card in partially withdrawn position.

Figs. 1 through 4 illustrate the skein package in connection with the formation of which the present invention is utilized. The 55 package is particularly adapted to hold a plurality of skeins 10 of yarn as embroidery yarn and the like, which skeins are made as described in my Patent No. 1,592,432, dated July 13, 1926. The skein is of roll form and is so 60 wound that the inner end 12 of the yarn projects beyond one end of the skein and the yarn is adapted to be withdrawn from the end and the inside of the skein, the skein preserving its formation until practically all of the yarn 65 has been withdrawn. The skein-holding package includes a rectangular card 14 of pressboard or similar material on the opposite ends of which a plurality of skeins are secured in parallel order with the free inner 70 ends of the yarn extended in the same direction. The card 14 is adapted to be reflexed upon itself along the line of fold 16 so as to bring the card into the shape shown in Figs. 1, 2 and 3. 75

Each skein of thread is held on the card by two spaced pairs of cooperating tabs 18, each pair being arranged in spaced edgewise relation and adapted to partially encircle and grip the skeins at the ends thereof. The tabs 80 are formed in the cards by punching two transverse lines or sets of longitudinally-aligned and transversely-spaced circular holes 20 in each end of the card so as to leave the material of the card therebetween to form the tabs 18. The card is slit along the line 22 close to the bottom edges of the holes to intersect the holes slightly above their lower edges in such manner as to separate the tabs, at similar ends, from the body of the card and 85 to provide the tabs, except the outermost tabs, with opposed approximately semi-circular cooperating notches in the opposite side edges between which the skeins of yarn are received and to provide openings 24 between the free ends of the tabs through which the skeins, by slightly compressing them, can be inserted within the circular notches in the tabs. The card is provided with crease-lines 90 26 which extend transversely of the card 100 along the upper edges of the openings 20, or along the bases of the tabs, to facilitate bending the tabs upwardly.

The skeins are inserted in position between

the tabs while they are in approximately perpendicular relation with the body of the card; and the tabs are held in this relation when the skeins are inserted by apparatus 5 hereinafter to be described. When the skeins are inserted in position between the tabs and the tabs are subsequently released, they are adapted to reflex by their inherent resiliency into an inclined position with respect 10 to the body of the card, or into some such position as illustrated in Fig. 3 wherein they are inclined approximately 45° with respect to the body of the card. As a result of the inclined position thereof, the tabs are caused 15 to bear down upon the skeins and so to clutch or grip them with substantial effect. The inclination of the tabs is directed against the direction of pull upon the ends 12 of the yarn of the skeins so that the tabs serve to hold the 20 skeins against withdrawal from the card when yarn is withdrawn.

After the skeins are applied to the card, a paper band 27 is wrapped around the card and over the skeins and the ends of the band 25 are pasted or otherwise secured together, thus additionally holding the skeins upon the card and also protecting the skeins against soil and concealing and securing the loose outer ends of the skeins. The band is adapted 30 to be narrower in width than the length of the skeins and is so applied that both ends of the skeins are exposed, whereby the color of the yarns in the skeins can be readily identified. The band also holds the folded card 35 from straightening out.

It is an object of this invention to provide a device adapted to reflex the tabs 18 of the card 14 into upright position and hold them in such position for the purpose of inserting 40 the skeins therebetween, thus to facilitate and expedite the card filling operation. The device embodying this invention is illustrated in Figs. 6 through 10. Said device comprises a flat horizontal base 30 which has a plurality 45 of projections 32 upstanding thereabove and arranged in a plurality of transverse lines corresponding to the lines of perforations 26 of the card 14, and spaced apart and so disposed as to be positioned beneath the tabs 50 18 of the card when the card is brought into contact therewith for the purpose of raising the tabs. The card 14 is adapted to be moved down upon said projections and for this purpose is adapted to be supported upon a flat 55 stiff plate 34, the rear end of which is hinged at 36 to an elevated ledge 37 carried by the base plate 30 and so arranged that when the plate 34 is moved downward, it will rest upon the top of the working face 31 of said 60 base 30. Said plate 34 is adapted to be moved downwardly by means of a rod 38 which has a loose connection with the under side of the plate and is adapted to be operated by a treadle or other suitable device not shown. 65 The plate 34 is adapted to be maintained in

elevated position by a suitably disposed spring 39. Said plate 34 is provided with sets of transversely-elongated slots or openings 40 thereof through which said projections 32 are adapted to extend when the hinged plate is upon the base plate. A thin and stiff cover plate 42 is secured at its rear and end edges and overlies the hinged plate and is spaced thereabove sufficiently to permit the insertion of a card 14 between the two 70 plates and to hold the card from upward displacement as the card is moved downwardly upon the projection 32. The plate 42 is held in the aforesaid relation by end spacer plates 44 and a rear spacer plate 45, which plates are disposed between the cover plate and the hinged plate and serve to locate the card 14 accurately in such position that its tabs will be engaged by the projections 32. Said cover plate 44 is provided with a plurality of elongated slots or openings 46 therein which are open at the front edge of the plate and overlie and preferably are substantially larger in all dimensions than the slots 40 in the hinged plate 34. In the use 80 of this device, a card 14 is inserted between the plates 34 and 42 to occupy the position illustrated in Fig. 7. The hinged plate is then moved down upon the face 31 of the base plate 30 or into the position illustrated 85 in Fig. 8. As a result of such movement, the projections 32 come into contact with the tabs 18 of the plate 14 and bind them into a perpendicular position as illustrated in Figs. 9 and 9 and hold them in such position for so long as the hinged plate is maintained upon the base plate. The projections 32 are preferably somewhat shorter than the tabs 18 so that, in the positions illustrated in Figs. 8 and 9, the tabs of the projections are somewhat below the tops of the tabs. The width of the projections preferably are not greater than the narrowest width of the tabs 18 or the width of the tabs between the semi-circular notches therein so that the projections do not overlie and block the notches. 100 The skeins are inserted into the openings 24 between the tabs to enter the notched portions of the elevated tabs as shown in Figs. 8 and 9. When the spaces between the tabs have been filled with skeins, the hinged plate is then released and is then moved upwardly 105 into the position shown in Figs. 6 and 10 by the spring 39 or by other means. In this position, the filled card can be withdrawn from the free end of the plate 34 in the manner shown in Fig. 10, the tabs passing through the open ends of the slots 46 of the cover plate 42. 110 When the tabs are free from the projections 34 they partially return from their original position by their inherent resiliency and assume an inclined position with respect to the card 14 as illustrated in Figs. 3 and 4 and thus grip the skeins and hold them in 115 120 125 130

such position. When the card is withdrawn from the device, the card can be folded about the line of fold 16 and have the holding band 26 applied, thus to complete the package.

5 I claim:

1. A device for raising the tabs of a skein-holding card comprising a card-holder, means providing a plurality of spaced projections extended in the same direction at one 10 side of said card-holder, and means to move said card-holder and projections toward each other into a position wherein the projections are within the card in the holder and bear against the tabs thereof.
- 15 2. A device for raising the tabs of a skein-holding card comprising a card-holder arranged to overlie and support the card except at the tabs thereof, and means providing a plurality of spaced projections disposed 20 beneath and extended upwardly toward said card-holder in the line of the tabs of the card, said card-holder characterized by being movable onto the projections, whereby to cause the tabs of the card to be engaged and raised 25 by said projections.
3. A device for raising the tabs of a skein-holding card comprising a card-holder including a flat plate adapted to overlie the card and having openings therein at the tabs 30 through which the tabs can extend, and a base having a plurality of spaced tab-raising projections disposed beneath and extended upwardly toward the openings in said plate in position to engage the tabs of the card, 35 said plate characterized by being movable into a position below the tops of said projections.
4. A device for raising the tabs of a skein-holding card comprising a card-holder including a flat plate adapted to overlie the card and having openings therein at the tabs through which the tabs can extend, and a base having a plurality of spaced tab-raising projections disposed beneath and extended 40 upwardly toward the openings in said plate in position to engage the tabs of the card, said plate characterized by being movable into a position below the tops of said projections and the openings in said plate characterized by having entrances thereto at one 45 edge of said plate through which the raised tabs can pass when the card is withdrawn from said plate.
5. A device for raising the tabs of a skein-holding card comprising a base having a plurality of spaced upstanding tab-raising projections, a card-holder including a thin flat plate disposed above and movable downwardly over said projections and having slots 50 therein adapted to overlie the tabs in the card and through which slots said projections can pass, said slots being open at one edge of said plate through which the raised tabs can pass when the card is withdrawn from the 55 holder.
6. A device for raising the tabs of a skein-holding card comprising a base having a plurality of spaced upstanding tab-raising projections, a card-holder including a thin flat plate disposed above and adapted to overlie 60 the card and having slots therein adapted to overlie said projections and the tabs in the card, said plate being movable downwardly over said projections into a position below the tops thereof, whereby to cause said projections to raise the card-tabs above the top of the plate in position to receive the skeins, said slots being open at an edge of the plate through which the raised tabs can pass when the card is withdrawn from the plate. 65
7. A device for raising the tabs of a skein-holding card comprising a base having a plurality of spaced upstanding tab-raising projections, and a card-holder disposed above 70 said projections and movable downwardly thereover, said card holder including a pair of superposed plates having a card-receiving space therebetween which is open at one edge of the holder, said plates having aligned slots 75 therein at which the tabs of the card are adapted to be located and into which said projections are adapted to pass, whereby to engage and raise the tabs above the top plate, the slots in the upper plate being open at the aforesaid edge of the holder through which the raised tabs can pass when the card is withdrawn from the holder. 80
8. A device for raising the tabs of a skein-holding card comprising a base having a plurality of spaced upstanding tab-raising projections, and a card-holder having a hinged connection with said base and disposed above 85 said projections and movable downwardly thereover, said card-holder including a pair of superposed plates having a card-receiving space therebetween which is open at one edge of the holder, said plates having aligned slots 90 therein at which the tabs of the card are adapted to be located and into which said projections are adapted to pass, whereby to engage and raise the tabs above the top plate, the slots in the upper plate being open at the aforesaid edge of the holder through which the raised tabs can pass when the card is withdrawn from the holder. 95
9. A device for raising the tabs of a skein-holding card comprising a base having a plurality of spaced upstanding tab-raising projections arranged in parallel rows, and a card holder disposed above said base and movable downwardly thereover, said holder including a pair of superposed plates having a card-receiving space therebetween which is open at one edge thereof and having sets of aligned slots therein adapted to overlie the tabs in the card and into which said projections can pass whereby to engage and raise the tabs into a vertical position above the holder, the slots in the upper plate being open at the aforesaid edge of the holder. 100
10. A device for raising the tabs of a skein-holding card comprising a base having a plurality of spaced upstanding tab-raising projections, a card-holder including a thin flat plate disposed above and movable downwardly over said projections and having slots 105 therein adapted to overlie the tabs in the card and through which slots said projections can pass, said slots being open at one edge of said plate through which the raised tabs can pass when the card is withdrawn from the plate. 110
11. A device for raising the tabs of a skein-holding card comprising a base having a plurality of spaced upstanding tab-raising projections, a card-holder including a thin flat plate disposed above and movable downwardly over said projections and having slots 115 therein adapted to overlie the tabs in the card and through which slots said projections can pass, said slots being open at one edge of said plate through which the raised tabs can pass when the card is withdrawn from the plate. 120
12. A device for raising the tabs of a skein-holding card comprising a base having a plurality of spaced upstanding tab-raising projections, a card-holder including a thin flat plate disposed above and movable downwardly over said projections and having slots 125 therein adapted to overlie the tabs in the card and through which slots said projections can pass, said slots being open at one edge of said plate through which the raised tabs can pass when the card is withdrawn from the plate. 130

through which the raised tabs can pass when the card is withdrawn.

10. A device for raising the tabs of a skein-holding card, comprising means providing a plurality of upwardly extended spaced projections, a card supporting plate movable downwardly over said projections and hav-

ing openings through which said projections may pass and having means to support the skein-holding card in position thereon with the tabs aligned with said projections. 10

In testimony whereof, I have signed my name to this specification.

JOHN L. BARRY.
